CLAIM

The ornamental design for a refrigerator, as shown and described.

DESCRIPTION

FIG. 1 is a front perspective view of a refrigerator, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is rear perspective view thereof;

FIG. 9 is an enlarged view of the encircled portion 9 of FIG. 1;

FIG. 10 is an enlarged view of the encircled portion 10 of FIG. 1;

FIG. 11 is an enlarged view of the encircled portion 11 of FIG. 1;

FIG. 12 is an enlarged view of the encircled portion 12 of FIG. 1;

FIG. 13 is an enlarged view of the encircled portion 13 of FIG. 6; and,

FIG. 14 is an enlarged view of the encircled portion 14 of FIG. 8.

The dash-dash broken lines illustrate portions of the refrigerator that form no part of the claimed design.

The dash-dot-dot-broken lines encircling enlarged portions of the refrigerator form no part of the claimed design.
